PRINTING AND DEPOSITING MECHANISM

Edward D. Rapisarda, Agawam, Mass.

Application January 18, 1935, Serial No. 2,406

8 Claims. (Cl. 107—29)

This invention relates to that type of candy making machinery in which measured amounts of fluid confection are deposited in molds; and has its principal use in connection with the operation of printing or forming a plurality of confection receiving depressions in a matrix of powdered starch or the like, and subsequently filling these depressions with fluid confection.

One object of the invention is to provide an improved and simplified mechanism by which a starch matrix, generally supported in shallow trays, may be printed with the required series of depressions, and these depressions may be filled with fluid confection whether the advance of the matrix through the machine is continuous or intermittent. A further object is to provide a simple construction of depositing pump. A further object is to provide a mechanism of this general character having ready adaptability to different sizes and spacings of the candy receiving depressions in the starch matrix. A further object is to provide a depositing mechanism having a wide range of adaptability in filling the depressions in a single matrix with a plurality of separate kinds of candy, either by filling separate groups of depressions with different kinds of candy or by placing different kinds of candy in various selected ways in the same depressions. Additional objects will appear as the mode of operation of the machine is described.

Referring to the drawings,

Fig. 1 is a side elevation of a portion of the preferred form of printing and depositing mechanism;

Fig. 2 is a continuation of Fig. 1, showing the manner in which the mechanism is given its reciprocating movement in synchronism with the forward movement of the starch matrix;

Fig. 3 is a section on line 3—3 of Fig. 2, taken on an enlarged scale;

Fig. 4 is a top plan view of the mechanism partly broken away to include the mechanism of Figs. 1 and 2 in a single view;

Fig. 5 is a section on line 5—5 of Fig. 4;

Fig. 6 is a fragmentary side elevation of the side of the machine opposite to that shown in Fig. 1;

Fig. 7 is a section on line 7—7 of Fig. 4, taken on an enlarged scale;

Fig. 8 is a perspective view of a portion of the depositing pump;

Fig. 9 is a section on line 9—9 of Fig. 4, taken on an enlarged scale;

Fig. 10 is a perspective detail of a separating device for the candy tank;

Fig. 11 is a plan view of the separating device; Fig. 12 is a transverse section through the separating device;

Fig. 13 is a detail of a plate forming part of the separating device;

Figs. 14 and 15 are perspective details, partly broken away, showing the operation of the depositing pump;

Figs. 16 and 17 are perspective details, partly broken away, showing modified forms of nozzle bars on the distributing pump;

Fig. 18 is a perspective detail showing the depositing mechanism arranged for depositing two different kinds of candy in alternate mold recesses;

Fig. 19 is a perspective section of the depositing mechanism arranged for depositing two kinds of candy side by side in the same mold recess;

Fig. 20 is a sectional plan of a portion of the mechanism shown in Fig. 19;

Fig. 21 is a detail of the candy produced by the mechanism of Figs. 19 and 20;

Fig. 22 is a perspective section of the depositing mechanism arranged for depositing two kinds of candy one above the other in the same mold recess;

Fig. 23 is a sectional plan of a portion of the mechanism shown in Fig. 22;

Fig. 24 is a detail of the mold recess showing the depositing action of the mechanism of Figs. 22 and 23;

Fig. 25 is a detail of the candy produced by the mechanism of Figs. 22 and 23;

Fig. 26 is a perspective section of the depositing mechanism arranged for depositing two kinds of candy in the same recess to produce a marbled effect;

Fig. 27 is a sectional plan of a portion of the mechanism shown in Fig. 26; and

Fig. 28 is a detail of the candy produced by the mechanism of Figs. 26 and 27.

The mechanism will be described in its preferred embodiment, dealing with the starch matrix when held in shallow trays forwarded with a continuous and uninterrupted motion through the machine. As the description proceeds, however, it will become apparent that neither the scope nor the utility of the invention is limited to this manner of handling the starch matrix; and that certain features of the invention are applicable when the trays are advanced intermittently, where the matrix is supported by other means than trays, or where other forms of molding media are used.

The machine is preferably carried on a single

frame, which is preferably composed of spaced supporting rails 39 laid directly on the floor 31 and suitably braced. These rails carry sprockets 32, turning on vertical shafts 33, and also sprockets 34 mounted on shafts 35. Around these sprockets pass opposed conveyer chains 36, bearing propelling lugs 37, the chains being guided and tightened by idling rollers or sprockets 38. The trays 39, in which the starch matrix 40 has previously been placed by other means, are guided in suitable ways and are carried in a continuously moving series through the machine by the lugs 37. The conveyer chains, as well as the rest of the mechanism to be described later, are driven from a shaft 41 which may receive its rotation from a motor or from some other part of the candy treating machinery. A worm gear connection 42 from this shaft drives a cross shaft 43 from which in turn bevel gear connections 44 drive the vertical shafts 33 previously mentioned, thus giving the conveyers a constant forward travel during the operation of the machine.

The printing and depositing mechanism is carried by a traveling frame 50 supported on rollers 51 which run on parallel tracks 52 (Fig. 3). This frame, with its attendant parts and the tank of fluid confection, is reciprocated back and forth once for each passage of a tray beneath it, and in order to keep down the frictional and inertial forces the frame is preferably made of an aluminum alloy. In order to reciprocate the frame a rock shaft 53 is mounted in it at one end. To this shaft is fixed an arm 54 pivoted at 55 to an adjustable link 56, the other end of which is pivoted on a tie rod 57 extending between the bearing brackets 58 which carry the shaft 43. A cam bar 60 is pivoted to the arm 54 at 61, and at its other end straddles the shaft 43 so as to be guided by it. A roll 62 is carried by the cam bar in position to engage a groove in a face cam 63 mounted on the shaft 43 and therefore in continuous rotation. The shape of this groove is so chosen that the frame 50 will travel during the operative part of its forward motion, at the same speed with which the trays 39 are advancing. In order to speed up the operation the rearward stroke is preferably made at a faster rate, and the periods of starting and stopping are made as smooth as possible in order to avoid shocks.

Passing across between the sides of the traveling frame 50, and movable with it, is a cam shaft 70 (Figs. 1 and 4). A worm gear 71 at one end of this shaft (Figs. 4 and 5) meshes with a worm 72 on a short longitudinal shaft 73 also journaled in the traveling frame. This shaft carries a pinion 74 meshing throughout the reciprocation of the traveling frame with a long gear 75 fixed on the drive shaft 41 and of a length somewhat greater than the reciprocative movement of the depositing mechanism. By this mechanism the cam shaft 70 is driven at a continuous rate which is unaffected by the stopping and starting of the reciprocating frame. A clutch member 76 is keyed at 77 to the cam shaft 70, and is formed with the usual groove to coact with a shipper arm 78 carried by a transverse shaft 79 operated by one or more handles 80. A coacting clutch member 81 is mounted on a sleeve 82 within which the shaft 76 rotates, and which serves as a discon-nectable driving means for the depositing pump to be described below.

Driven directly by the shaft 70, and therefore unaffected by the clutch, is a cam 83 operating a rock arm 84 fixed to a transverse shaft 85. At 75 its ends the shaft carries arms 86 (Fig. 1) each of

which bears a block 87 slidably mounted on a vertical shaft 88. The motion of the block relative to the shaft is limited in an upward direction by a collar 89, and motion in a downward direction is limited by a spring 90 bearing against a second collar, preferably in the form of an adjustable nut 91. Each shaft is threaded at 92 into a member pivoted to one end of a printer head 93, which may be of usual form, bearing molding projections 94 adapted to enter the starch and to form the molding recesses therein. By rotating the two threaded shafts 88 the printer head can be adjusted vertically, this being accomplished by worm gears 95 on the upper ends of the shafts, engaging worms (not shown) mounted on a cross shaft 96 which can be rotated manually by a crank 97. These parts have been broken away in Fig. 4 to disclose the parts below them. In order to prevent any but vertical motion the printer head is provided with lugs 98 running in vertical ways 99 on the frame 50. It will be apparent from the above description that the printer head will descend upon the starch filled tray during the forward motion of the latter, pressing the starch into form and withdrawing from it while the printer head and the tray are traveling forwardly at the same rate of speed. A repeated pressure with an intermediate period of release can obviously be secured by a proper design of the cam 83.

The liquid candy to be deposited in the molded recesses thus formed in the starch is carried on the traveling frame 50 within a tank 100. This tank is provided with brackets 101 through which pass shafts 102. Each shaft is held against vertical movement in the bracket by collars 103, and is threaded at its lower end into a bracket 104 on the frame so that by rotating the shafts the tank can be raised and lowered. A worm wheel 105 fixed to the top of each shaft meshes with a worm (not shown) on a common transverse shaft 106 provided with an operating handle 107, thus providing a convenient means for raising and lowering both sides of the tank simultaneously. In order to prevent rocking movement of the tank it is provided with one or more lugs 108 running in vertical guides 109 on the frame.

Since in order to keep the weight as low as possible the tank is preferably made of aluminum, a metal which undergoes a chemical reaction in the presence of some kinds of candy, it is preferable to provide the tank with a lining 110 (Fig. 9) of copper. This may be held within the tank by an upper frame 111 (Fig. 1) and by members 112 and 113 (Fig. 9) at the bottom, held in place by bolts 114. The sheet copper lining is extended between the tank body and these various holding members, preferably with the interposition of a gasket 115. If the lining 110 is spaced from the wall 100 as indicated a jacket 116 is provided through which water or steam may be circulated by means of fittings 117 (Fig. 1).

At the bottom of the tank is located a depositing pump which possesses many novel characteristics. Among the chief of these features is an extreme simplicity of construction lending itself particularly to the construction of a multiple or gang pump. The mechanism is, so to speak, built around a plate 120 (Figs. 16 and 18) from which a plurality of fingers 121 arise. These fingers are arranged in regular rows and columns. Over these fingers are placed a plurality of tubes 122 preferably formed of short lengths of rectangular bronze tubing, the tubes being merely slipped over the fingers as shown in Fig. 75

8. Individually the tubes need not be secured in place; collectively they are held by a frame composed of end pieces 123 and side pieces 124 secured together in any desired way and having somewhat the effect of a printer's chase. Preferably, in order to secure rigidity and to furnish another confining wall, some or all of the fingers are held to a stationary plate 125 by screws 126 as shown in Fig. 18. This construction provides a plurality of individual pumps, in which the pistons are formed by the walls 127 of the tubes (Fig. 20); the pistons moving in confined spaces the bottom wall of which is formed by the plate 120, the top wall is formed by the plate 125, the side walls by the sides 128 of the tubes and the end walls by the fingers 121. The volumes of the confined spaces are alternately increased and diminished by the reciprocation of the tube assembly as a whole.
20. The plate 120 is secured by screws 130 (Fig. 7) to side bars 131 which serve as a removable frame upon which the entire pump mechanism is carried, permitting it to be removed from its position underneath the tank for cleaning and for replacement of parts. Each of the side bars fits against a shoulder 132 in the corresponding member 112, and has a beveled portion 133 resting upon the upper side of a gib 134. The gibs serve the double purpose of permitting the bars 131 and the parts associated with them to be slid endwise to remove them from the machine, and of furnishing a means of clamping the bar firmly when in place. For the latter purpose the gibs are provided with slots 135 (Fig. 9) through which pass bolts 136 (Fig. 7) secured in the members 112. By sliding the gibs endwise, as by the use of a clamp screw 137 (Fig. 9) threaded through an extension 138 of member 112, they can be caused to rise up on the bolts 136 and thus press the bars 131 firmly against the shoulders 132, preventing movement of the bar or leakage of candy from the tank during the operation of the machine.
- Sliding over the upper plate 125, and serving as the bottom of the tank, is an inlet cut-off plate 140 having a series of ports 141 positioned in it as will be described below. Sliding underneath the plate 120 is a discharge cut-off plate 142 having ports 143. The ports 141 and 143 are adapted to register respectively with pairs of ports 144 in the plate 125 and with pairs of ports 145 in the lower plate 120. A nozzle plate 146 is located snugly underneath the discharge cut-off plate 142 in a manner permitting its ready removal and replacement when it is desired to change the type of product being manufactured. The description of the various forms of discharge nozzles can best be considered in connection with the operation of pump mechanism as a whole, and will accordingly not be taken up at this point. The nozzle plate is formed with lateral shoulders 147 (Fig. 7) which engage side members 148 held, together with spacing bars 149, and the plate 120, against the side bars 131 by means of the screws 130. The nozzle plate can thus be slipped transversely out of the pump assembly, being retained in position when in place by one or more set screws 150 (Fig. 9) passing through the side bars.
70. The mechanism for sliding the assembly of tubes 122 relative to the stationary fingers 121, together with the mechanism for sliding the cut-off plate 140 and 142, will now be described. Referring first to the tube assembly (Fig. 8), one of the end members 123 is provided with a vertical hole 155 and a laterally opening hole 156 to receive respectively a pin 157 and a link 158 (Fig. 9). This link is coupled to an arm 159 (Figs. 4 and 6) pinned to the bottom of a shaft 160 carried in bearings 161 on the side of the traveling frame 50. To the upper portion of the shaft is pinned an arm 162 connected by a link 163 with a block 164 adjustable in a slot 165 of a rocker 166 fixed on an operating shaft 167. A screw 168 is threaded into the block and is held against axial motion on the rocker by a collar 169 and a hub 170 engaging opposite sides of a block 171 pivoted on the rocker and having a hole through which the screw passes loosely. The screw is provided with a handle 172 by means of which the position of the block 164 on the rocker may be changed, even during the operation of the machine, thus changing the stroke given to the tube assembly. The slot 165 is preferably made concentric with the pivot between the link 163 and arm 162, so that this adjustment will not change the symmetry of the motion of the tube assembly with respect to the longitudinal center line of the tank. As shown in Fig. 4, shaft 167 carries a crank 175 pivoted to a link 176 straddling the sleeve 81 on shaft 70 and provided with a roll 177 engaging a groove in a cam 178 carried by that sleeve.
- The inlet cut-off plate 140 is connected by a link 180 (Figs. 4 and 6) with an arm 181 extending from a sleeve 182 rotatable on the shaft 160. A second arm 183 on this sleeve is joined by a link 184 with an arm 185 projecting from a sleeve 186 rotatable on the rock shaft 167. A rocker 187 on this shaft is slotted similarly to the rocker 166 and in a like manner carries an adjustable pivot for a link 188. This link is pivoted to a reciprocating member 189 straddling the sleeve 81 and a guide roll 190, and carrying a cam roll 191 fitting into a groove in a cam 192 fixed to that sleeve. The adjusting mechanism, being similar to that already described, has been omitted from the drawings in order to show parts which would otherwise be concealed by it. The discharge cut-off plate 142 has a link 195 connecting it to an arm 196 on a stub shaft 197 mounted in bearings 198 on the side of the frame 50. An arm 199 on this shaft and a similar arm 200 on the sleeve 182 are connected together by a link 201 so that the shaft 197 and the sleeve 182 always move together, while the inlet cut-off plate and the discharge cut-off plate, by reason of the opposing positions of the arms 181 and 196, will move simultaneously in opposite directions.
- Before taking up in detail the operation of the pumping mechanism it is desirable to emphasize the fact that the back and forth movements of the tube assembly and the two cut-off plates takes place during the motion of the traveling frame 50 in the direction of movement of the starch-carrying trays. As a matter of fact the effective movement of the pump mechanism is confined to that portion of the forward motion of the frame in which it is moving at the same linear speed as the trays, so that exact alignment is maintained between the nozzles and the printed depressions in the starch at all times when there is a flow of confection through the nozzles. This action is permitted by the type of drive given to the traveling cam shaft 70. It will be recalled that this shaft derives its motion from the engagement of pinion 74 with the long and constantly rotating gear 75. The rotation of shaft 70 is thus continuous and entirely independent of the reciprocation of the frame on which it is mounted.

It is thus possible to have either one, two, or more pumping operations during the coaction of the device with a single tray, a feature which permits many useful and novel modes of operation.

The operation of the pump may be understood most clearly from a comparison of Figs. 14 and 15. In these figures the pump has been cut through the middle of a row of tubes 122. It will be seen that the sides 128 of the tubes lying parallel to the direction in which the tube assembly reciprocates form parts of the pumping chambers, while the walls 127 lying at right angles to this direction of reciprocation form in effect the pistons of the pumps. In Fig. 14 the tube assembly is shown as having nearly reached the end of its travel towards the right in that figure, and the path of the liquid candy is shown by arrows. The inlet ports 144, 141 are open to the chambers which lie at the left of the pistons, and the ports 143, 145 are open from the right-hand chambers to the ports 215 in the nozzle bars. In Fig. 15 the tube assembly has moved to the opposite end of the stroke, the right-hand chambers now drawing from the tank and the left-hand chambers delivering to the nozzle bar ports 217.

By suitable shapes of the ports in the nozzle bars various methods of depositing candy may be followed, the nozzle bars being made readily replaceable as described above in order to permit the various methods to be practiced as desired. The arrangement shown in Fig. 18 is used when two separate kinds of candy are to be deposited in two alternating series of molding recesses and can also be used for a single kind of candy where half of the recesses are filled on one stroke of the tube assembly and the other half on the reverse stroke. As pointed out above, the two strokes are completed during the motion of the depositing mechanism in synchronism with the tray.

In order to permit the use of two kinds of candy in the same tank the latter is provided with a partition formed to divide the upper part of the tank into two approximately similar compartments and the lower part of the tank into two series of interdigitated chambers connected respectively with the two compartments. This partition includes a plate 205 (Figs. 10, 11, and 12) which form the upper longitudinal portion of the partition, and which is bolted at 206 to a plate 207 having a series of fingers 208 bent so that they slant alternately in opposite directions. To these fingers are soldered or otherwise secured a series of triangular transverse partition members 209 provided along their slanting sides with oppositely bent flanges 210 (Figs. 11 and 13) by which they may be fastened to the fingers. It will be apparent from a comparison of Figs. 10 and 18 that when the partition is in place in the tank with its bottom surface resting on the plate 149, the members 209 will divide the tank into two alternating series of chambers each chamber of which runs the full width of the tank and includes a complete line of holes 141. The two series of chambers are connected respectively to the two main divisions of the tank produced by the partition 205, and thus can contain two distinct kinds of candy without intermixing. If desired, of course, the two sides of the tank may contain the same kind of candy, making it unnecessary to remove the partition when the type of work is changed.

Referring to Fig. 18 again, and assuming that the tank contains different kinds of candy on the two sides of the partition 205, it will be seen that

alternate rows of holes 141 will be fed respectively with the two kinds of candy. The holes are shifted relatively to the partitions 209 as the port plate 140 is shifted back and forth to align each hole 141 alternately with the holes 144 of each pair, but do not pass underneath the partitions. Holes 141 can be understood, therefore, as receiving constantly only one type of candy. The holes 141 which move back and forth between the pair of holes 144 on opposite sides of one of the pump fingers 121 will receive candy A, those corresponding to the next line of fingers 121 will receive candy B, and so on. The result is that the pump chambers are arranged in double alternating rows, those on opposite sides of the same row of fingers 121 carrying the same kind of candy, and the next pair carrying the other kind. The pump chambers in each pair operate alternately as the tube assembly moves back and forth, and as the outlet port plate 142 reciprocates each of its holes 143 move between a pair of holes 145 communicating with a pair of pump chambers carrying the same kind of candy. The holes 143 also connect with a series of holes 215 in the stationary nozzle bar 146, each of the latter holes having a nozzle 216 connected to it. As shown in Fig. 18, alternate holes 215 are connected to their nozzles by short passages 217 serving in this case merely to space the nozzles evenly in accordance with the spacing of the molding recesses 218. These recesses will with this arrangement of apparatus be filled with candy A and candy B in rows as indicated, giving a method of depositing an assortment of candies with but one pump mechanism.

The arrangement shown in Figs. 19 and 20 varies only in the form of the nozzle bar. In this case the nozzle bar has one set of nozzles 220 positioned directly opposite the holes 145 and a second set 221 located adjacent the nozzles in the first set but connected to those holes 145 next but one along the line by a passage 222. As shown in Fig. 20, alternate passages 222 extend in opposite directions and overlap so that all the holes 145 are accounted for. Bearing in mind that each pair of holes 145 is alternately made operative by the sliding of the outlet port plate 142, and therefore that every other one is operative simultaneously, it will be seen that in this case each adjacent pair of nozzles 220 and 221 will discharge together, each delivering a different type of candy. This produces a candy piece C shown in Fig. 21 in which the two sides 223 and 224 are of different composition corresponding to the kinds A and B.

The form of nozzle plate shown in Figs. 22 and 23 is used to give a double candy structure with horizontal rather than vertical stratification. The structure is somewhat similar, one nozzle 225 of each pair being positioned directly opposite one of the holes 145; but the other nozzle 226 of each pair is connected by a passage 227 to the hole 145 corresponding to the next pump chamber feeding the other kind of candy and on the opposite stroke. Instead of the two nozzles of a pair operating simultaneously as in the form shown in Figs. 19 and 20, they here operate successively, causing the candy of one kind to flow in after the flow of the other has ceased. The candy C' is shown in the molding recesses in Fig. 24 and after removal therefrom in Fig. 25. Due to the method of connection of the nozzles the position of the two types of candy is reversed in adjacent molds, as appears from Figs. 24 and 25.

Still a third method of placing two kinds of

candy in a single recess is shown in Fig. 26. The passage 222 is here the same as in Figs. 19 and 20, but the two nozzles 220 and 221 are replaced by a single larger nozzle 230. Since both kinds of candy are delivered simultaneously through the nozzle a marbling effect is produced as shown at C' in Fig. 28.

Figs. 16 and 17 indicate the facility with which the apparatus may be modified in another direction. It may be that it is desired to use the depositing mechanism with starch trays having a spacing of molding recesses different from the spacing of the pump tubes 122. In such a case the nozzle bar 146 is provided with nozzles 235 spaced as desired, and recesses 236 or 237 provided to connect one nozzle to a plurality of holes 145 on opposite sides of the fingers 121 and therefore fed with the same kind of candy if more than one kind is being used. In Fig. 16 each nozzle connects with four holes, two being operative on one stroke of the tube assembly and the other two on the opposite stroke. In Fig. 17 each nozzle connects with three holes 145, one being operative on one stroke and the other two on the opposite stroke. This affords a way of depositing larger candies than can be handled by one pump chamber; or smaller candies with larger spacing if the stroke of the tube assembly is cut down.

The various forms of nozzle bar shown are intended as illustrative only, and are by no means exclusive. They show, however, how the same pump assembly can be used to produce varying results merely by changing the nozzle bar, which is made easily detachable for this purpose, and by changing the stroke of the tube assembly by the conveniently located handle 172. In prior constructions a similar change could be obtained only by substituting a completely new pump assembly. With these modifications indicated other forms of nozzle bar can be readily devised by those skilled in the art to meet special requirements.

I claim:

1. A multiple depositing mechanism for fluent material comprising a pair of port plates connected by a plurality of fingers in a rectangular array of spaced rows and columns, each port plate having a hole on each side of each finger, a cellular structure each cell of which surrounds a finger and extends between the port plates, means for reciprocating the cellular structure as a unit; a top and a bottom cut-off plate each having one hole corresponding to each finger-separated pair of holes in the port plates, and means for reciprocating the cut-off plates to cause the holes in the cut-off plates to register alternately with the holes of each pair in the port plates.

2. A multiple depositing mechanism for fluent material comprising a pair of port plates connected by a plurality of fingers in a rectangular array of spaced rows and columns, each port plate having a hole on each side of each finger, a cellular structure each cell of which surrounds a finger and extends between the port plates, means for reciprocating the cellular structure as a unit, a nozzle bar spaced below the lower port plate, an upper cut-off plate above the upper port plate, a lower cut-off plate between the lower port plate and the nozzle bar, each cut-off plate having one hole corresponding to each finger-separated pair of holes in the port plates, and means for reciprocating the cut-off plates to cause the holes in the cut-off plates to register alternately with the holes of each pair in the port plates.

3. A multiple depositing mechanism for fluent material comprising a pair of port plates connected by a plurality of fingers in a rectangular array of spaced rows and columns, each port plate having a hole on each side of each finger, a cellular structure each cell of which surrounds a finger and extends between the port plates, means for reciprocating the cellular structure as a unit, a nozzle bar spaced below the lower port plate and having downwardly opening nozzles and ducts each leading from a point opposite a hole in the lower port plate to one of said nozzles, an upper cut-off plate above the upper port plate, a lower cut-off plate between the lower port plate and the nozzle bar, each cut-off plate having one hole corresponding to each finger-separated pair of holes in the port plates, and means for reciprocating the cut-off plates to cause the holes in the cut-off plates to register alternately with the holes in each pair in the port plates.

4. A multiple depositing mechanism for fluent material comprising a pair of port plates connected by a plurality of fingers in a rectangular array of spaced rows and columns, each port plate having a hole on each side of each finger, a cellular structure each cell of which surrounds a finger and extends between the port plates, means for reciprocating the cellular structure as a unit, a tank having separating means arranged to deliver two separate kinds of candy to alternating finger-separated pairs of holes, a nozzle bar spaced below the lower port plate and having downwardly opening nozzles and ducts each leading from a point opposite a hole in the lower port plate to one of said nozzles, an upper cut-off plate between the upper port bar and the tank, a lower cut-off plate between the lower port plate and the nozzle bar, each cut-off plate having one hole corresponding to each finger-separated pair of holes in the port plates, and means for reciprocating the cut-off plates to cause the holes in the cut-off plates to register alternately with the holes in each pair of port plates.

5. A multiple depositing mechanism as claimed in claim 4, in which the ducts in the nozzle bar connect corresponding holes of adjacent finger-separated pairs in the lower port bar with one or more nozzles positioned to deposit in a single molding recess, whereby two separate streams of different kinds of candy are delivered to one molding recess during a single stroke of the cellular structure.

6. A multiple depositing mechanism as claimed in claim 4, in which the ducts in the nozzle bar connect noncorresponding holes of adjacent finger-separated pairs in the lower port bar with pairs of nozzles each pair positioned to deposit in a single molding recess whereby two separate streams of different kinds of candy are delivered successively to one molding recess on successive strokes of the cellular structure.

7. A multiple depositing mechanism for fluent material comprising a divided candy holding tank, a multiple chambered two-stroke depositing pump having its chambers connected in sets to the different divisions of the tank, and depositing passages opening in pairs each pair arranged to deposit candy in a single molding recess and the passages of each pair leading to separate pump chambers of the same set but operative on alternate strokes of the pump mechanism whereby two different kinds of candy may be deposited successively in the same molding recess.

8. A multiple depositing mechanism for fluent material comprising a divided candy holding tank,

a multiple chambered two-stroke depositing pump having its chambers connected in sets to the different divisions of the tank, and depositing passages opening in pairs, each pair arranged to deposit candy in a single molding recess and the passages of each pair leading to separate pump

chambers of the same set and operative on the same stroke of the pump mechanism whereby two different kinds of candy may be deposited simultaneously in the same molding recess.
